OSCILLATOR SYSTEM

Jennings B. Dow, Long Beach, Calif.

Application March 15, 1933, Serial No. 660,966

4 Claims. (Cl. 250—36)

(Granted under the act of March 3, 1883, as
amended April 30, 1928; 370 O. G. 757)

My invention relates broadly to electron tube oscillator systems.

One of the objects of my invention is to provide a simplified arrangement of an electron-coupled oscillator circuit when, for example, it is desired to maintain certain elements other than the cathode at a low high-frequency potential with respect to a shield box or with respect to earth.

Another object of my invention is to provide a low power oscillator of the electron-coupled type wherein the cathode heating system may be simplified by a special arrangement of indirectly heated cathode tubes.

Other and further objects of my invention will be understood from the specification hereinafter following by reference to the accompanying drawing in which:

Fig. 1 shows one form of circuit wherein an ordinary oscillator circuit is employed but with the anode element of the electron tube at substantially zero high-frequency potential with respect to the shield box and ground.

Fig. 2 shows a detailed view of the heater-cathode construction of an ordinary indirectly heated cathode type of electron tube.

Fig. 3 shows another form which the heater-cathode construction may take.

Fig. 4 shows an electron-coupled type of oscillator circuit employing the principles of my invention and Fig. 5 shows another form of such circuit employing the principles of my invention.

As a matter of convenience the same reference numbers will be employed to designate items which have similar functions in each of the figures.

In certain forms of electron tube oscillation generators, it is desirable to maintain one of the elements other than the cathode at a low high-frequency potential with respect to the shield box or with respect to ground. It is well known that any one of the elements of a three element tube type of oscillation generator may be so maintained as a low high-frequency potential provided the other two elements are allowed to assume such high-frequency potentials as are dictated by their positions in the circuit. For example, Fig. 1 shows such a circuit wherein an electron tube 1 having a cathode heater 2, a cathode 3, a control grid 4 and an anode element 5 is connected in circuit for the generation of oscillations. Reference character 6 designates a resonant circuit consisting of inductance 7 and capacity 8. One end of this resonant circuit is connected through capacity 9 and grid leak re-

sistance 10 to the control grid 4. The other end of resonant circuit 6 is connected to a point 11 which may be made common to the source of heater energy 12, the source of anode energy 13, the shield box 14 only a section of which is shown and to earth at 15. Reference character 16 designates a by-pass capacity which offers a low reactance path for high frequency currents between anode 5 and point 11. The cathode is connected to a point 17 along the inductance 7.

In the circuit of Fig. 1, it will be noted that the cathode is at a high frequency potential above that of the heater 2 by an amount determined substantially by the product of the high frequency current in inductance 7 and the reactance of that portion of the inductance between points 17 and 11. The insulation between heater 2 and cathode 3 must be constructed to withstand this difference of potential.

Fig. 2 shows the conventional heater-cathode construction wherein reference character 18 designates the insulating tube between the heater 2 and electron emitting cathode 3.

Fig. 3 shows a modified heater-cathode construction in which the heater 2 and the cathode 3 are separated by space instead of a solid insulator as in Fig. 2. In the arrangement shown in Fig. 3, the heater 2 is a single filament stretched between two supports 19 and 20. The cathode is held in position by bridge wires 21 which are secured to insulating members 22 which in turn are secured to the heater supports 19 and 20. The form of construction shown in Fig. 3 is desirable in cases where the high-frequency potential difference between the heater and cathode is large.

The circuit of Fig. 4 is that of an electron-coupled oscillator employing the principles of my invention. The basic oscillator is similar to that of Fig. 1 except that the screen-like anode element 5 is used in lieu of the ordinary anode 5 in Fig. 1. The second anode 23 in Fig. 4 is connected through resonant circuit 24, consisting of capacity 25 and inductance 26, to battery 27 which in combination with battery 13 supplies the second anode with energy. By-pass capacity 28 bridges battery 27 and offers a low reactance path for the high-frequency impulses of current flowing to the second anode 23.

The circuit of Fig. 5 is similar to that of Fig. 4 except that the cathode 3 instead of being connected to inductance 7, is connected to a separate inductance 29 which is coupled to inductance 7 for producing the desired regenerative action for oscillation. Also, in the circuit of Fig. 5 the work

circuit of the second anode 63 consists merely of a suitable resistance 30.

It will be understood that while I have shown battery sources of energy for the heaters and anode supply that any other suitable sources may be used, for example, alternating current may be employed for the heaters. Also many other obvious arrangements of the circuits are possible, for example, any of the well known basic oscillation 10 generators may be employed.

While I have described my invention in certain preferred embodiments, I desire it to be understood that modifications may be made and no limitations are intended other than are imposed 15 by the scope of the appended claims.

The herein described invention may be manufactured and used by or for the Government of the United States of America for governmental purposes without the payment of any royalty thereon.

20 What I claim as new and desire to secure by Letters Patent in the United States is as follows:

1. An oscillation generator having an electron tube including an indirectly heated cathode, a heater insulated from said cathode, a control grid 25 and screen-like anode, sources of supply potential and connections thereto for actuating said tube, an input circuit connecting said control grid and cathode, an output circuit connecting said screen-like anode and cathode, means for regeneratively coupling said circuits, a second anode within said tube and a work circuit included in series connection between said second anode and said screen-like anode and means including said screen-like anode for electrostatically shielding 30 the electron stream of said tube between said cathode and screen-like anode from said second anode, and a circuit of relatively low reactance at the frequency of the generated oscillations disposed between said heater and said screen-like 35 anode.

2. An oscillation generator having an electron tube including an indirectly heated cathode, a heater insulated from said cathode, a control grid and screen-like anode, sources of supply potential and connections thereto for actuating said tube, an input circuit connecting said control grid 40

and cathode, an output circuit connecting said screen-like anode and cathode, means for regeneratively coupling said circuits, a second anode within said tube and a work circuit included in series connection between said second anode and said screen-like anode and means including said screen-like anode for electrostatically shielding said cathode and control grid from said second anode, and a circuit having a relatively low reactance at the frequency of the generated oscillations disposed between said heater and screen-like anode.

3. An oscillation generator having an electron tube including an indirectly heated cathode, a heater insulated from said cathode, a control grid, a screen-like anode and a second anode, sources of supply potential and connections thereto for actuating said tube, an input circuit connecting said control grid and cathode, an output circuit connecting said screen-like anode and cathode, means for regeneratively coupling said circuits, a shield box at least partly surrounding said generator, circuits having a low reactance at the frequency of the generated oscillations between said screen-like anode and said shield box, and between 90 said heater and said shield box, and output means for said generator disposed between said second anode and said screen-like anode.

4. An oscillation generator having an electron tube including an indirectly heated cathode, a heater insulated from said cathode, a control grid, a screen-like anode and a second anode, sources of supply potential and connections thereto for actuating said tube, an input circuit connecting said control grid and cathode, an output circuit 100 connecting said screen-like anode and cathode, means for regeneratively coupling said circuits, a shield box at least partly surrounding said generator, a work circuit disposed in series connection between said second anode and said screen-like anode and circuits of low reactance at the frequency of the generated oscillations between said screen-like anode and said shield box and between said heater and said shield box.
